UNITED STATES PATENT OFFICE.

ISAAC LEVY, OF BROOKLYN, NEW YORK.

DESIGN FOR A CHANDELIER OR ARTICLE OF SIMILAR NATURE.

Application filed August 10, 1927. Serial No. 23,045. Term of patent 3½ years.

To all whom it may concern:

Be it known that I, ISAAC LEVY, a citizen of the United States, and a resident of Brooklyn, county of Kings, and State of New York, have invented a new, original, and ornamental Design for a Chandelier or Article of Similar Nature, of which the following is a specification, reference being had to the accompanying drawing, forming a part hereof.

The figure in the drawing shows a perspective view of the chandelier which has arms for the support of candles or drop lights.

I claim:

The ornamental design for a chandelier or article of similar nature substantially as shown.

ISAAC LEVY.
